UNITED STATES PATENT OFFICE.

LUDWIG POSCH, OF JERSEY CITY, NEW JERSEY, ASSIGNOR OF ONE-HALF TO
MAXIMILIAN LANCEK, OF NEW YORK, N. Y.

VISE.

1,405,325.

Specification of Letters Patent. Patented Jan. 31, 1922.

Application filed July 1, 1921. Serial No. 481,830.

To all whom it may concern:

Be it known that I, LUDWIG POSCH, a citizen of the United States, and a resident of Jersey City, in the county of Hudson and State of New Jersey, have invented a new and Improved Vise, of which the following is a full, clear, and exact description.

This invention relates to gripping devices and particularly to an improved construction which may be used in vises of all kinds to grip articles of any shape and firmly hold the articles in position.

The object in view is to provide a gripping structure for vises and other mechanism which will grip articles of different sizes and shapes and will at the same time accommodate itself to the particular shape of the article being gripped.

Another object of the invention is to provide a gripping jaw formed with a number of nested parts which will automatically assume a straight line or an irregular line as pressure is brought to bear thereon so as to accommodate different shaped articles.

A still further object, more specifically, is to provide a vise with a pair of rounded sockets in the opposing jaws and gripping means fitted into said sockets arranged in groups with automatically adjusting gripping parts.

In the accompanying drawings—

Figure 1 is a top plan view of the device disclosing a gripping jaw structure embodying the invention.

Figure 2 is a side view of the structure shown in Figure 1.

Figure 3 is a top plan view of the jaw shown in Figure 1, the same being shown removed and in gripping action for gripping a diamond-shaped article.

Figure 4 is a sectional view through Figure 1 approximately on line 4—4.

Figure 5 is a detail perspective view of one of the gripping parts shown in Figure 3.

Figure 6 is a front view of an arc-shaped member adapted to carry two of the gripping parts shown in Figure 5, said member embodying certain features of the invention.

Referring to the accompanying drawings by numeral, 1 indicates the base of a vise which in general design may be of any kind and which is provided with jaws 2 and 3. These jaws may be arranged so that one will be stationary and the other movable or both movable. The detail construction of the base 1 and the jaws 2 form no part of the present

invention except the formation of the jaws 2 and 3 so as to present arc-shaped sockets 4 for receiving the crescent-shaped members 6 and 7. The members 6 and 7 are loosely arranged in the sockets 4 so as to freely turn or slide in said sockets. Suitable covering and retaining plates 8 and 9 are provided for preventing accidental removal of these members. Each of the members 6 and 7 is provided with arc-shaped sockets 10 and 11 for receiving crescent-shaped members 12 and 13, which crescent-shaped members in turn are provided with a pair of sockets 14 and 15 for receiving crescent-shaped members 16 and 17. Each of the members 16 and 17 is provided with two arc-shaped notches 18 and 19 for receiving the substantially crescent-shaped clamping members 20 and 21. The contact or gripping face of members 20 and 21 may be as shown in the drawing or may have some other configuration without departing from the spirit of the invention. However, these members are positioned to rotate on a central axis while fitting in the notches 18 and 19. The same is true of members 15 and 16 as well as members 12 and 13 of the crescent shaped member 7. All of these members are adapted to automatically move or adjust themselves to present a straight, curved or irregular clamping surface to an article according to the shape of the article as shown in Figure 3. For instance, when the parts are in the position shown in Figure 1 and it is desired to insert a diamond-shaped article, as shown in Figure 3, the jaws are opened wide enough to receive the article and then the article placed in position and held until the jaws are closed. During the closing action the various crescent-shaped members will automatically move to the position shown in Figure 3 and will consequently, grip evenly the article. In this way, the article may be firmly gripped in place with the desired pressure without crushing any part thereof.

In forming the various crescent-shaped members they are preferably provided with overhanging shoulders 22 and 23 at each end as shown in Figures 4 and 5. These overhanging shoulders are adapted to fit over a tongue structure 24 on the next adjacent crescent-shaped member. This construction holds the various members together in their proper central position while allowing a free rotary movement thereof for permitting automatic adjustment and, conse-

2
5
quently, an even pressure over the article to be clamped. A diamond-shaped article is shown in Figure 3 but it is evident that flat, round or any desired shaped article 5 may be readily clamped with an even pressure over the clamped surface.

10 The invention has been illustrated as being applied to an ordinary vise but it is evident that it may be used on a pipe vise or any other form of vise and if desired chucks for lathes as well as other machinery and in all these uses, automatically adjusts itself to take care of any irregularity in the article clamped.

15 What I claim is:—

A vise of the character described, comprising a body, a pair of jaws mounted on the body, and a gripping structure for each

of said jaws, each gripping structure consisting of a plurality of elongated nested members, said members each being arc-shaped in cross section and having at their upper and lower ends correspondingly shaped shoulders overhanging the convex face of the member and having their opposing faces undercut, all of the members except the outermost ones having arc-shaped grooves in their ends forming intermediate dove-tail tongues having concave faces, fitting upon the adjacent members between the shoulders thereof and engaged by the said shoulders, whereby the said members are free to rotate on their own axes, but are securely held against accidental displacement.

LUDWIG POSCH.
